mington, Del., a corporation of Delaware

Application July 18, 1941, Serial No. 403,007

1 Claim. (Cl. 183—2.5)

The present invention relates to apparatus for the removal of air, or other gases, contained in liquids. More specifically, it relates to the removal of air and other gases from viscose in a continuous manner.

While it is apparent that the apparatus of the present invention is suitable for removing air from various liquids, for convenience, the invention will be discussed with specific reference to the deaeration of viscose.

In the production of articles such as yarns or pellicular structures from viscose compositions, it is necessary to remove the air, or other gases, from the compositions before spinning the yarn or casting the film. If this air is not removed, the air bubbles pass through the extrusion orifices causing broken filaments during the spinning or, in the case of films, air bubbles, or holes, will be formed in the film.

Air is present in viscose in two forms, that is, as occluded air which appears as bubbles and dissolved air. If a body of viscose is subjected to a vacuum, the bubbles present becomes larger because of the decreased pressure and tend to rise more rapidly to the surface. The dissolved air forms bubbles and gradually comes out of solution at the surface of the viscose. These actions, of course, become faster the thinner the viscose layer becomes. If a film of viscose is passed continuously over a vertical surface, the same actions take place, but at any reasonable film velocity, under low vacuum, i. e., a pressure below atmospheric pressure but above that at which the viscose boils at any given temperature, air bubbles formed at the film are folded back into the viscose and do not escape. If a high vacuum is employed, such that the pressure is below the vapor pressure of the viscose at any given temperature, water is boiled from the viscose and the removal of air is greatly accelerated since water vapor evaporates into the air bubbles causing them to swell and burst. Also, dissolved air is removed by the sweeping effect of water being boiled from the film. Deaeration of the film will be complete if the film is sufficiently thin and the boiling sufficiently violent that evaporation takes place throughout the full depth of the film.

A number of methods have been proposed and used to remove the air from viscose compositions. In one of these, the viscose was treated under the action of a vacuum in a kneading machine. In another method, the one which is probably the most commonly used, the solution is subjected to a high vacuum, in some cases as high as 28

inches of mercury, while holding it in large rest tanks during the ripening of the viscose. During this period, the viscose may be passed through a series of rest tanks under this high vacuum. It is further known to cause the viscose to be spread in a thin film in a container and to subject it to a vacuum which preferably does not cause boiling of the viscose.

There have been a number of disadvantages in the above prior art processes. In most cases, the air is not completely removed. While the occluded air is difficult to remove completely, it is even more difficult to remove a substantial part of the dissolved air. In cases where it is desired to spin a high index viscose, the time necessary for removing the air is sometimes so long that the desired index is passed before the air is removed. The known types of apparatus for removing air from viscose will gradually build up skins on the walls of the apparatus as the result of the spattering of the viscose. In some cases, large particles of gelled viscose from the skin formation fall into the solution causing filtering difficulties. It is also necessary to clean the apparatus often because of the skin formation.

It is, therefore, an object of this invention to provide an improved apparatus for removing occluded and dissolved air, or other gases, from liquids.

It is a further object of this invention to provide an apparatus for the continuous deaeration of viscose.

It is another object of this invention to provide an apparatus which will greatly decrease the time necessary for removing air from viscose.

It is still another object of the present invention to provide an apparatus for removing air from viscose which will prevent or greatly decrease the viscose skin formation.

Other objects of this invention will appear hereinafter.

The objects of this invention are accomplished, in general, by continuously flowing a viscose in a layer or film of substantially uniform thickness over the side walls of a chamber, subjecting the film to a high vacuum such that the viscose boils, collecting the deaerated viscose in the bottom of the tank, and continuously withdrawing the solution from the vacuum chamber. This chamber is preferably so designed that all wetted portions of said chamber are washed by a continuous flow of viscose and that spattering of the boiling solution on dry portions of the chamber is substantially eliminated, thereby substantially preventing viscose skin formation.

Preferably, the temperature differential between the incoming viscose and the boiling point of the viscose is maintained constant by regulating the vacuum in the chamber, whereby the quantity of water evaporated per unit volume of viscose will remain substantially constant.

The details of the invention will be better understood by reference to the following detailed description when taken in connection with the accompanying illustrations, in which:

Figure 1 is a vertical sectional view of a deaerating apparatus suitable for use in accordance with the present invention.

Figure 2 is a top plan view of the apparatus shown in Figure 1.

Figure 3 is an enlarged sectional view showing a detail of the viscose distributing device of the deaeration apparatus.

Figure 4 is an enlarged sectional view of a modified form of distributor device.

Figure 5 is a diagrammatic elevational view, with parts shown in section, of a modified form of deaeration apparatus constructed in accordance with the present invention.

Referring to the drawings, reference numeral 11 designates a deaeration tank having concave top and bottom sections and constructed sufficiently heavy to withstand a high vacuum. A conduit 13 is connected to the top of the tank 11. The conduit 13 is provided with a pressure gauge 14 and a throttling valve 15 and a vacuum pump 17 whereby to impart a vacuum to the tank. A manifold 19 is positioned about the upper periphery of the tank. A header conduit 21 is connected to the manifold at opposite sides of the tank. A viscose composition is fed to the header 21 through conduit 23. A plurality of connecting conduits 25 are connected between the manifold 19 and the tank 11. As shown in Figure 1, the connecting conduits 25 pass through the cylindrical wall of the tank 11 into the distributor 27 which is described in greater detail below. The distributor 27 is positioned a sufficient distance below the top of the tank 11 to prevent spattered particles of viscose, due to the boiling of the latter, from contacting the top of the tank. The distributor directs the viscose downwardly into contact with the side wall 33 of the tank. The tank is preferably provided with an annular ring 35 which will function to redistribute the flow of the viscose to avoid the formation of rivulets. The viscose level in the tank 11 is designated by line 37. This level is preferably maintained substantially constant. The deaerated viscose is withdrawn from the tank 11 through conduit 39 positioned in the bottom of the tank. The conduit 39 is provided with valve 40 and pump 41. The tank 11 is also provided with a glass gauge 45 which will indicate the level of the viscose. If desired, the gauge 45 may be connected to the viscose outlet conduit 39 by means of by-pass conduit 47. The by-pass conduit 47 functions to pass viscose from the outlet line back into the tank 11 to avoid building up coagulated viscose in the conduits leading to the gauge 45. A temperature bulb 49 is positioned in the manifold 19. The bulb transmits an accurate temperature reading to the temperature gauge 51. A similar temperature bulb 53 is positioned against the internal periphery of the tank at a distance slightly above the level of the viscose 37. The temperature bulb 53 is connected to a temperature gauge 55 whereby to transmit an accurate

temperature reading of the temperature of the viscose on the interior of the tank.

Referring to Figure 3 of the drawings in which the distributor 27 is shown in enlarged detail, the distributor comprises essentially a U-shaped annular member 60 positioned against the internal periphery of the tank 11. The U-shaped member 60 comprises a front lip 61 which may, if desired, have a serrated top edge 63. A viscose directing hood 65 is positioned over the top of the open U-shaped member. The directing hood comprises a lip 67 which is positioned in overlapping relationship to lip 61 so that the viscose flowing from between the two lips is directed downwardly along the lip 61 into the tank. A flow shield 69 is positioned between the bottom of lip 61 and the internal periphery of the tank 11. The viscose will follow flow shield 69 and will then flow along the internal periphery of the tank wall.

Referring to Figure 4, numerals 71 and 71a designate a tank in which the upper section is of greater diameter than the lower section. The internal periphery of the upper section 71 and the internal periphery of the top of lower section 71a form the two legs of the U-shaped member of the distributing device. The bottom of member 71 is bent inwardly at right angles to contact the lower section 71a thereby completing the U-shaped member. In this modification the connecting conduits 25 are preferably provided, at the end projecting within the U-shaped member, with an opening 43 on only one side thereof. It will be readily apparent that the series of connecting conduits 25, each provided with openings on only one side of their inwardly projecting ends will impart a circular motion to the viscose passing into the annular U-shaped member of the distributor. In this form of distributor device the hood member 65 is also provided with a downwardly projecting lip 67 overlapping the upwardly projecting lip 61 whereby to direct the issuing viscose downwardly along the wall of the tank 71a. It will be noted that in this form of device the viscose will flow solely in a vertical film since the internal periphery of the tank is a continuation of the lip 61. This form of device is preferred over that shown in Figure 3 since the flow of viscose along the internal periphery of the tank wall is found to be more uniform.

The operation of the above-described device is as follows: The viscose from a feed tank (not shown) is passed into conduit 23, then into header 21 and from header 21 through manifold 19 and connecting conduits 25 into the distributor 27. The vacuum pump 17, in the meantime, has evacuated the tank 11 to a sufficient amount that the viscose at the temperature at which it passes into the distributor is caused to boil. In other words, the pressure on the surface of the viscose as it flows from the distributor is slightly less than the vapor pressure of the viscose. The viscose as it issues from between the lips 61 and 67 boils and froths with a considerable amount of spattering and at the same time flows downwardly along the lip 61 in a continuous film. The film flows down along the flow shield 69, unless the device is constructed as shown in Figure 4, and then downwardly along the internal periphery of the wall of the tank. As a result of the boiling and frothing of the viscose, the contained air is removed together with a very small amount of water. The evaporation of the water induces a cooling of the viscose.

cose composition as it flows downwardly along the internal periphery of the tank wall. As soon as the viscose has cooled sufficiently that the vapor pressure is equal to or less than the pressure of the surrounding atmosphere the boiling will cease. The vacuum imparted to the tank is preferably such that the boiling point of the viscose is at a temperature of from 10° to 35° C. below the temperature of the incoming viscose. The film of viscose flowing along the internal wall of the tank is preferably caused to flow over an obstruction such as ring 35 whereby the film is re-formed to prevent the formation of rivulets on the wall of the tank. The viscose, before it reaches the constantly maintained level 37, is caused to pass a temperature bulb 53 on the internal periphery of the tank. The vacuum may be manually adjusted by throttling valve 15. The vacuum will be adjusted from the temperature readings of temperature gauges 51 and 55 to maintain constant the temperature differential between these two readings. By maintaining this temperature differential constant, the amount of water removed from the viscose will remain constant and the viscose composition will be maintained uniform. The viscose is constantly withdrawn through outlet conduit 39 controlled by valve 40 and pump 41. The level of the viscose in the tank will be maintained substantially constant by observation of the gauge glass 45 and control of the pump 41. The conduits of the gauge glass may be occasionally cleaned by passing viscose from the outlet conduit 39 through by-pass 47. It may also be desirable at intervals to pass a cleaning fluid such as water through the entire length of the gauge glass to maintain the viscose therein free from gelation.

The operation of the apparatus provided with the construction of the distributor shown in Figure 4 will be identical to that above described. The film of viscose will be maintained with a more uniform thickness since the flow along the internal periphery of the device will have no change in direction.

Referring to Figure 5 of the drawings, the deaerating apparatus is provided with automatic means for maintaining constant the temperature differential between the incoming viscose and the boiling point of the viscose. The conduit 13 through which the tank 11 is evacuated is connected with a small tube 93 which leads to a pressure gauge 95 by means of which the vacuum in the tank may be visually determined. The conduit 13 is also provided with a butterfly valve 83 by means of which the suction of the vacuum pump may be throttled. The butterfly valve 83 is automatically operated by motor diaphragm 85. The motor diaphragm is in turn operated by means of the pressure contained in tube 87 leading thereto. The pressure in the tube 87 is determined by the temperature differential between bulbs 49 and 53 positioned respectively in the manifold 19 and on the internal periphery of the tank slightly above the level of the viscose. The temperature bulb 49 is provided with a capillary tube 50 containing an expansible hydrocarbon liquid and said capillary tube is connected to a differential temperature controller 91. The temperature bulb 53 is similarly provided with a capillary tube 52 which is also connected with the controller 91. The controller 91 may be any device which will function to regulate an air pressure acting on motor diaphragm 85 in accordance with the temperature

differential of the two temperature bulbs 49 and 53. Inasmuch as the controller per se is no part of the present invention, the details thereof are not set forth herein. One example of an instrument suitable for use in this capacity is the Taylor "Fulscope" controller adjustable sensitivity type with automatic reset (122R) differentially connected with the two temperature bulbs as shown and described on page V-6 of the instruction booklet published in 1939 by the Taylor Instrument Companies, Rochester, New York. The vacuum conduit 13 is also provided with a shutoff valve 15 and a three-stage steam jet pump 81. The apparatus otherwise shown in Figure 5 is substantially identical to that shown in Figure 1 of the drawings above described.

The operation of the device disclosed in Figure 5 is as follows: The tank 11 is evacuated to the point where the vacuum is sufficiently high to cause a boiling of the viscose composition which is to be deaerated. The viscose is passed into the distributor and into the tank in the same manner as above described with reference to the apparatus of Figure 1. The viscose froths and boils and spatters towards the center of the tank and at the same time a film of the viscose passes downwardly into the body of the viscose contained in the lower portion of the tank. The temperatures of the viscose in the manifold and in the tank adjacent the level of the body of the viscose in the lower portion of the tank cause an expansion or contraction of the hydrocarbon liquid in the bulbs 49 and 53 respectively. In case of an increase in temperature, the expanded liquid in bulb 49 is forced through capillary conduit 50 into the controller device 91, and the expanded hydrocarbon liquid in bulb 53 passes through capillary conduit 52 into controller 91. The controller 91 is provided with air under a constant pressure which pressure is used by the controller mechanism 91 to operate the motor diaphragm 85 through conduit 87 to open or shut the butterfly valve 83 thereby controlling the pressure in the tank 11. Should the viscose flowing into manifold 19 having a gradually rising temperature, the bulb 49 will operate through the controller mechanism 91 and motor diaphragm 85 to slightly close the butterfly valve 83 thereby decreasing the evacuation in the tank 11 to maintain constant the amount of boiling of the viscose flowing into the tank. The film of viscose having the slightly increased temperature will flow into contact with bulb 53 which will compensate the controller mechanism to again maintain constant the temperature differential between the incoming viscose in the manifold and the boiling point of the viscose on the internal periphery of the tank slightly above the viscose level 37. Should the temperature of the viscose remain the same but the volume of viscose increase, there will be no immediate function of the bulb 49. From the increased flow of the viscose more water vapor will be formed than can escape through the outlet throttled by the butterfly valve, so the pressure will increase and the boiling point of the viscose will increase. The temperature of the viscose at the bulb 53 will rise causing the controller 91 to slightly open the valve 83 thereby reducing the pressure in the tank to again establish the temperature differential selected. The vacuum in the tank can always be checked visually by the pressure gauge 95 connected to the vacuum conduit 13. The viscose is withdrawn through outlet conduit 39 provided with valve 40 and pump 41 in the same manner as above described with refer-

ence to the apparatus of Figure 1. The pump 41 used to remove the deaerated viscose continuously from the tank 11 is preferably a standard constant flow gear pump.

The following specific example is given to illustrate the process of the present invention, it being understood that the details set forth in this example are not to be considered as limiting the invention thereto.

Example I

A 7% cellulose, 6% caustic viscose having a salt index of 4 and having a temperature of 21° C. is pumped into the continuous deaerating tank at a rate of 245 pounds per minute. The viscose is directed downwardly against the side walls of the tank and flows in a continuous film having a thickness of approximately $\frac{1}{2}$ inch down the side walls of the tank and into the body of viscose in the lower portion of the tank. The body of viscose is maintained at a substantially constant level in the lower portion of the tank. The tank is subjected initially to a vacuum corresponding to 29.2 inches of mercury, and the viscose film boils and froths as the air and a small quantity of water are removed therefrom. The evaporation of the water induces a cooling of the viscose and the viscose film, as it reaches the body of viscose in the lower portion of the tank, has cooled to a temperature of 18° C., and has ceased to boil. The deaerated viscose is continuously pumped from the bottom of the tank at the rate of 244 pounds per minute and sent to a supply tank for a viscose rayon spinning machine. The almost negligible decrease in the amount of viscose withdrawn from the tank per minute from the amount introduced per minute is caused by the small amount of water evaporated during deaeration. This very small quantity of water may be added to the viscose before deaeration. Temperature readings are frequently taken of the incoming viscose and viscose just before it passes into the body of viscose in the tank. The vacuum in the tank is regulated to maintain the temperature differential between the two readings at 3° C., whereby the amount of water evaporated per unit volume of viscose is maintained substantially constant.

The following procedure may be used to determine whether the dissolved air as well as the occluded air has been removed by the continuous deaerator device. When using a bright viscose, i.e., a viscose which does not contain a pigment or delusterant, a 125 cc. Ehrlemeyer flask is filled to a depth of $\frac{1}{2}$ inch. The flask is then subjected for half a minute to a vacuum sufficiently high to cause boiling of the viscose, that is, the pressure on the viscose is lowered to or below the vapor pressure of the viscose. If there is no dissolved air present, there is very little foaming and any small bubbles formed collapse immediately as the vacuum is released. If there is any dissolved air present, there will be some foaming and a number of small bubbles will form in the body of the viscose. These bubbles do not disappear when the vacuum is released, but require an appreciable length of time to redissolve. This may vary from several minutes to two or three hours depending upon the amount of air present in the bubbles and upon the condition of the viscose, such as viscosity, temperature and so forth.

Since small bubbles cannot be seen under the surface of dull viscose, a slightly different procedure is used from that described above. A similar sample is taken and subjected to a high

vacuum, but not sufficiently high to cause boiling. If air is present, either dissolved or occluded, it becomes evident by the formation of small bubbles which rise to the surface and burst. This takes place slowly so that the sample should be left under vacuum for three or four minutes.

The invention is not limited to the use of any particular evacuating device since any means of obtaining the vacuum may be used, which will produce a vacuum high enough to cause boiling of the viscose. While the three-stage steam jet vacuum pump is preferred, other devices such as a piston vacuum pump, a centrifugal vacuum pump, and other pump or jet action devices may be used.

It is desirable to use a large cylindrical tank as a vacuum chamber and as a surface over which the viscose film may flow. Preferably, the tank is sufficiently large to prevent the spattering of the viscose onto any surfaces which are not continuously washed with the flowing film of viscose. The top of the tank is preferably at least 18 inches above the distributor device to avoid spattered particles from contacting the top. A suitably sized tank may be one having a diameter of $6\frac{1}{2}$ feet and a height of $9\frac{1}{2}$ feet. Although cylindrical tanks are preferred other shaped containers may, however, also be used; for example, a tank having on its inner surface large corrugations wherein the line of corrugation is parallel to the axis of the tank may be used as a means of increasing the surface area over which the viscose flows without increasing the diameter of the tank. It is also possible to use multiple tanks such as one large tank with a smaller tank inside wherein a film of viscose is provided on the inside surface of the large tank and on the outside surface of the small tank.

The apparatus of this invention is capable of 40 suitably deaerating, in a continuous manner for a long period of time, from 0.3 to 3 pounds of viscose per minute per circumferential inch of the inside surface of a tank in which the viscose film flows downwardly a distance of 4 feet. 45 The capacity of the device is independent of the vacuum, provided said vacuum is sufficient to cause boiling of the viscose. The output of the device may be varied depending mainly upon the rate at which the viscose is introduced into the tank provided suitable deaeration is obtained.

The thickness of this film of viscose flowing down the sides of the tank will vary with the amount of viscose fed to said tank. The film should not be so thick that only part of the thickness of the film boils during its flow inside the tank. The entire film should boil to obtain suitable results.

In the above specific example, the viscose was brought into the deaeration tank at a temperature of 21° C. and was removed at a temperature of 18° C., a temperature differential of 3° C. Since the temperature drop of the viscose as it passes through the tank is a measure of the amount of water evaporated therefrom, the temperature drop is regulated and should not be too great. It would be possible to operate this device with a temperature differential as much as 20° C., but it is preferred that the temperature drop not exceed 7° C. The temperature at which the viscose may be introduced into the tank may vary from 15° C. to 40° C. or in some cases even higher. At temperatures lower than 15° C., the viscose becomes so viscous that it flows too slowly for practical operation. The effect of temperature on ripening of the viscose should be taken

into consideration when operating at the higher temperatures. In deaerating liquids other than viscose, temperatures other than those given above may be used depending upon the properties of the liquid.

While the apparatus of the present invention has been described in terms of its use in deaerating viscose, it is understood that it is not limited thereto and that it may be used to treat other viscous liquids, such as solutions of cellulose derivatives, vinyl compounds, including polyvinyl acetate, polyvinyl alcohol, polyvinyl acetal, etc.; resins, either synthetic or natural, including rosin, dammar, alkyd, methacrylates, etc.; and synthetic linear polymeric materials including polyamides, polyesters, and the like.

By the use of the process and apparatus of the present invention, numerous advantages in the deaeration of viscose are obtained. The viscose may now be deaerated almost instantaneously although for operating reasons it remains in the tank for about 20 minutes, whereas heretofore it took about 20 to 30 hours in most cases. The flow of viscose through the system is continuous which is an improvement over the vacuum rest tank process in most common current use. Much less equipment and space is needed for the present apparatus than heretofore. Improved deaeration is obtained since not only is all of the occluded air removed, but practically all of the dissolved air as well.

Viscose tends to form skins and to gel if left stagnant. The present apparatus is so designed that all wetted portions of the tank wall are washed by a continuous flow of viscose and spattering on dry portions is eliminated. By this means, stagnant areas in the deaeration system are eliminated thereby permitting the apparatus to operate for long periods of time without stopping for cleaning said apparatus.

It is well-known that viscose ripening is a function of both time and temperature. The more accurately the time element can be controlled, the higher the temperature which can be used. Since viscose undergoes some cooling as it enters the deaerator because of the evaporation of water, it is possible to ripen at a considerably higher temperature than at present and control

the time during which the viscose is at the higher temperature by ejecting it into the deaerator. The time of ripening of the viscose may, therefore, be considerably shortened while still maintaining an accurate control of the salt index.

Excess carbon disulfide in the viscose may be removed in the deaerator and may be recovered if desired. By this means, it is possible in the preparation of the viscose to use an excess of carbon disulfide and to subsequently recover this excess from the viscose in the deaerating system.

In the past, considerable care has been taken not to use any viscose preparation procedures which would tend to cause air to be occluded in the viscose. Because of the high efficiency of the present process and apparatus for removing air, many procedures not heretofore practical may be used. For example, centrifuges and disintegrators which tend to beat or throw air into the viscose may be used provided the viscose is later deaerated according to the present invention.

Since it is obvious that many changes and modifications can be made in the above-described process and apparatus without departing from the nature and spirit of the invention, it is to be understood that the invention is not to be limited to the above-described details except as set forth in the appended claim.

30 I claim:

A viscose deaerating apparatus comprising a cylindrical container, a vacuum pump connected to said container, a viscose manifold, a plurality of viscose inlet means connecting said manifold to said container near the top thereof, a U-shaped annular viscose distributing trough positioned on the internal periphery of the container and immediately adjacent said inlet means, and a frustum-shaped viscose directing member contacting and extending downwardly from the inner bottom edge of the trough to the side wall of said container whereby to direct the flow of viscose issuing from said trough in the form of a film downwardly and into contact with the uppermost exposed portion of the side wall below said trough.
